Inventor

United States Patent Office.

LUCIUS L. WOODRUFF, OF CLEVELAND, OHIO.

Design No. 4,720, dated March 14, 1871.

DESIGN FOR AN INKSTAND.

The Schedule referred to in these Letters Patent and making part of the same.

To all whom it may concern:

Be it known that I, LUCIUS L. WOODRUFF, of Cleveland, in the county of Cuyahoga and State of Ohio, have invented a new and useful Design for a Bottle to be used as an Inkstand, and the same is to be made of glass; and I do hereby declare that the following is a full and exact description of the form and construction of the same, reference being had to the annexed drawings making a part of this specification, in which—

Figure 1 is the perspective view of front end and side; and

Figure 2, a view of the rear end and side.

In which—

The letter A, on the rear end, represents the place for the label;

B represents the gable roof; and
C, the chimney, which will be the neck of the bottle.

Claim.

What I claim as my invention, and desire to secure by Letters Patent, is—

This particular shape of cottage-bottle, with a gable roof, as shown in the annexed drawings, to be used for containing writing-inks.
